 Maier & Neustadt(57) **CLAIM**

The ornamental design for a rocker pad support insert, as shown and described.

DESCRIPTION

FIG. 1 is a top perspective view of a rocker pad support insert showing our new design;

FIG. 2 is a top plan view thereof;

FIG. 3 is a front elevational view thereof;

FIG. 4 is a left side elevational view thereof, the right side elevational view being a mirror image;

FIG. 5 is a bottom perspective view thereof;

FIG. 6 is a bottom plan view thereof; and,

FIG. 7 is a rear elevational view thereof.
